UNITED STATES PATENT OFFICE.

PETER J. DOCKRAY, OF WOONSOCKET, RHODE ISLAND.

STOP-MOTION FOR COMBERS AND THE LIKE.

1,252,095.

Specification of Letters Patent. Patented Jan. 1, 1918.

Application filed September 5, 1914. Serial No. 860,401.

To all whom it may concern:

Be it known that I, PETER J. DOCKRAY, a citizen of the United States, residing at Woonsocket, in the county of Providence and State of Rhode Island, have invented 5 certain new and useful Improvements in Stop-Motions for Combers and the like, of which the following is a specification, reference being had therein to the accompanying drawing.

This invention provides a stop-motion for use in association with combers and other fiber-treating machines, and it is an object of the invention to provide efficient and reliably-acting means for stopping such a machine, the functioning of which is dependent upon occurrence of certain conditions in the material passing through the machine.

While it is not the intention to limit the 20 application of the invention to any particular machine for treating material while in substantially continuous movement, the invention, for purposes of explanation, is described herein as associated with a cotton-comber. In such a machine the stop-motion should operate when there is a lap run out, a lap upon a detaching-roll, a choked trumpet, a pulling apart of sliver on the table, a pulling apart of sliver between the 25 draw-box calendar-rolls and the coiler, and a roll lap in the draw-box, and the stop-motion provided by this invention is arranged to stop the machine on occurrence of any of these conditions.

The present invention pertains more particularly to a power-shifting device whose action is instituted to stop the machine, upon occurrence of one or more of these conditions in the material, by the closing of an 30 electric circuit effected by one or more circuit-closers responsive to conditions in the material, as, for example, such as are shown by copending applications Serial Numbers 127,295, 127,296, and 127,297, filed October 45 23, 1916, which are divisions of this application.

When read in connection with the description herein, the details of construction and arrangement of parts contemplated by the 50 invention will be apparent from the accompanying drawings, forming part hereof, wherein an embodiment of the invention as applied to a cotton-comber is disclosed.

While the embodiment of the invention 55 exemplified herein now is considered a preferable one, it is to be understood that it is

not the intention to be limited necessarily thereto in interpretation of the claims, as changes within the limits of the claims and adaptations to other machines can be made 60 without departing from the nature and spirit of the invention.

Like reference-characters refer to corresponding parts in the views of the drawings, of which—

Fig. 1 is a side view of a lap run-out motion;

Fig. 2 is a view thereof looking in direction of the arrow, Fig. 1;

Fig. 3 is a plan view of the lap run-out motion and other parts, and it includes a diagrammatic exposition of the electric circuit and power-shifting mechanism;

Fig. 4 is a view in elevation of the belt-shifting mechanism;

Fig. 5 is an enlarged view in elevation of a portion of the belt-shifting mechanism;

Fig. 6 is a sectional view on the line 14—14, Fig. 5;

Fig. 7 is a plan view of parts shown by 80 Fig. 5;

Figs. 8, 9, 10, and 11 are views illustrative of different positions of the pawl-controlling spring.

In order properly to explain the operation 85 of the power-shifting mechanism to which the present invention pertains, a circuit-closer, such as hereinbefore mentioned, arranged to initiate operation of the shifting mechanism when there is a lap run out, is 90 shown by Figs. 1, 2, and 3 of the drawings.

In these figures, 63 designates the lap; 64 the rear rolls for the lap carried on a shaft 65; 66 circular racks or ratchet-wheels rotatably mounted on the shaft 65 (one at each 95 end of roll 64) and rotating normally with the rolls under the influence of frictional contact imposed by washers 67 and collars 68, which keep the wheels against the ends of the rolls; 69 the front rolls for the lap 100 carried on a shaft 70; and 71 a longitudinal frame member of the machine of which these members are parts.

Fixedly secured to the frame member 71 by bolts 72 and insulated by non-conductive 105 material 73 there are several brackets or arms 74, of which one is shown, extending rearwardly between adjacent ends of the rolls 69 and under the shaft 70. These arms or brackets support and have securely held 110 in their ends by set-screws 75 a longitudinally-extending rod 76, which the material

73 insulates from the machine. Upright standards 77 are secured to the rod 76, one opposite to each rack 66. Each standard has extending from its upper end in parallel relation to the rolls a pin or stub-shaft 78 on which is journaled an arm 79 intermediate its ends. The arm 79 on one side of its pivotal point extends as a weighted pawl 80 toward one of the racks 66, with which its 10 end is capable of engagement. The arm on the other side of its pivotal point has a non-conductive lap-contact member 81 extending therefrom into a slot 82 in one of the lap-aprons 83 of the machine. Each pair of lap-rollers, it will be seen, has a pivoted arm 79 at each end, and one of the contact members 81 extends into each side portion of the lap-apron.

The relative arrangement of the parts is 20 such that, when the lap is passing normally over the apron, the pawl 80 will be kept out of engagement with the rack 66 by contact of the member 81 with the lap. When the lap runs out and there is no lap to keep the 25 member 81 down, the weighted pawl, which over-balances the other side of the arm 79, will be permitted to fall into engagement with the rack, whereby a circuit is closed and the machine caused to stop.

30 A power-shifting mechanism as contemplated by the present invention to have its operation initiated by a circuit-closer such as shown by Figs. 1, 2, and 3 or by others hereinbefore mentioned is exemplified by 35 Figs. 4, 5, 6, 7, 8, 9, 10, and 11 of the drawings.

A support 84 of the shifting-mechanism is shown secured to the frame of the machine of which the mechanism is a part. The support 40 has journaled thereon a cam-carrying shaft 85, which is rotated constantly while the machine is in operation by worm-gears 86. The shaft has loose thereon and normally rotating therewith a ratchet-wheel 87, which on one side seats against an abutment 88 on the shaft and on the other side has a spiral cam-face 89. This cam-face is 45 co-operable with a correspondingly-shaped cam-face 90 of a sleeve 91 keyed and longitudinally movable on the shaft. The cam-faces of the ratchet-wheel and sleeve normally are held in closed contact by a spring 92 on the shaft between the free end of the sleeve and an abutment 93 on the shaft. A 50 lever 94 fulcrumed at 95 on the support has a bifurcated end 96, which straddles the shaft 85 and abuts the end of the sleeve opposite to the cam-face thereof. The other end of the lever is connected by a rod 97 with a hand-shifting-lever 98 and with a belt-shifter 99 arranged to transfer the drive-belt of the machine from one to the other of fast and loose pulleys 100 and 101 on a main drive-shaft 102 of the machine.

65 The arrangement is such that, when the

cams are closed, the drive-belt will be on the fast pulley and the machine will be in operation. When the sleeve is moved longitudinally of the shaft by means now to be described, the sleeve in contact with the bifurcated end of the lever will swing the lever and shift the belt to the loose pulley and stop the machine.

An insulated box or casing 103 is secured to the support 84 above the shaft 85, and a 70 pawl 104 is hung pivotally at its upper end in this box in such manner that its lower end normally will be out of engagement with the ratchet-wheel 87. One or more electromagnets 105 within the box have their cores 75 positioned opposite to the upper portion of the pawl and so arranged that, when the magnets are energized by closing of a circuit on movement of one or more circuit-closers, such, for example, as that shown 80 by Figs. 1, 2, and 3, they will draw the lower end of the pawl into engagement with the ratchet-wheel and stop rotation of that wheel. When the wheel is stopped, the sleeve 91 continuing to rotate will be moved 85 longitudinally of the shaft by coaction of the cam-faces and the belt-shifting lever will be swung to transfer the belt from the fast to the loose pulley and the machine stopped.

A curved spring 106 is secured at one end to a side of the magnet-box 103, and at its other end it is in contact with the side of the lever 94 while that lever is in the position it has under the normal conditions of the 100 machine in operation. When the lever has moved and shifted the belt from the fast to the loose pulley, it is released from contact with the spring and a circuit through the machine is opened, as hereinafter described, 105 this release being at a time that the sleeve has reached about one-quarter of its longitudinal movement in order to open the circuit through the machine as soon as the pawl has engaged the ratchet-wheel or shortly thereafter. When the sleeve has reached the limit 110 of its movement, it is forced back home by the spring 92.

A guide 107 is secured to and depends from the side of the magnet-box opposite to 115 the lever 94, and through this guide extends an end portion of a flat spring 108, which at the other end is pivoted and rigidly secured to the side of the lever on the same side of its fulcrum as the bifurcated end. The 120 spring extends behind the pawl 104 or on the same side thereof as the magnets, and it has a shoulder or curved portion 109 deflected toward the pawl and normally having position between the pawl and guide 125 107, as shown by Figs. 8 and 9. Normally the pawl is out of contact with the spring, as shown by Fig. 8. When the pawl is drawn into engagement with the ratchet-wheel, it moves close to the spring, as shown 130

by Fig. 9. Then, on movement of the lever, the spring is drawn thereby so that its shoulder rides over the pawl, as shown by Fig. 10, and the spring is arranged so that it has a tendency in this position to push the pawl out of engagement with the ratchet-wheel. However, the power of the spring is not sufficient to disengage the pawl from the ratchet-wheel against the combined opposition of the drawing power of the magnets while the circuit is closed and the push of the ratchet-wheel against the pawl while the sleeve is being forced longitudinally by the coacting cam-faces; but, as soon as the circuit is opened by movement of the lever from contact with the spring 106 and the push of the ratchet-wheel ceases on return home of the sleeve, the tension or power of the spring then is sufficient to, and does, move the pawl from engagement with the ratchet-wheel.

Referring now to Fig. 3, which shows diagrammatically the electric circuit, 110 designates any suitable source of electricity, 25 from one pole of which leads a conductor 111 connected to the winding of the magnets 105, and from the magnet-winding there leads a conductor 112 to a rod 25, in electrical connection with which rod are sliver-controlled circuit-closers such as are disclosed more particularly in the hereinbefore mentioned divisional applications. From the other pole of the electric source leads a conductor 114 through the insulated magnet-box 103 to the spring contact member 35 106 normally in contact with the lever 94, whereby the machine itself is made a part of the circuit. A conductor 113 leads from the rod 25 to the insulated rod 76 of the lap-controlled circuit-closer. When any of the 40 circuit-closers operates, the circuit is closed through the machine and the insulated rods 25 and 76 and held closed until the contact-spring 106 is released from the lever 94, 45 during which time the magnets are energized and the belt is caused to shift and the machine stopped as already explained. For example, when the lap runs out and there is no lap to keep the member 81 down, the 50 weighted pawl 80 will fall into engagement with the rack 66 and thereby close the circuit.

On release of the spring 106 from the lever, the circuit is opened, and there is no 55 danger of an operator receiving an electric shock during the time he is restoring the material to the normal condition of movement from the condition that caused the circuit to close.

Having thus described my invention, what I claim as new, and desire to secure by Letters Patent, is—

1. A stop mechanism comprising a member normally having continuous movement, 65 a stop member movable into engagement

with and thereby stopping said member, a power-shifting device arranged to be moved by coaction with said member when stopped, a stop-releaser, and means causing said stop-releaser to push in releasing direction against 70 said stop member after institution of action of said power-shifting device.

2. A stop mechanism comprising a member normally having continuous movement, 75 a pawl movable into stopping engagement with and normally disengaged from said member, a power-shifting device arranged to be moved by coaction with said member when stopped, and a spring connected with said device and arranged to be tensioned in 80 releasing direction against said pawl by movement of said device.

3. A stop mechanism comprising a member normally having continuous movement, 85 a pawl movable into stopping engagement with and normally disengaged from said member, a power-shifting device arranged to be moved by coaction with said member when stopped, and a spring connected with said device and having a shoulder positioned 90 to exert releasing pressure against said pawl on movement of said device.

4. A stop mechanism comprising a member normally having continuous movement, 95 a pawl movable into stopping engagement with and normally disengaged from said member, a power-shifting device arranged to be moved by coaction with said member when stopped, a spring connected with said device and arranged to be tensioned in 100 releasing direction against said pawl by movement of said device, an electric circuit, an electro-magnet controlled by said circuit and arranged to move said pawl to stopping position, and a circuit-closer for said circuit. 105

5. A stop mechanism comprising a member normally having continuous movement, 110 a pawl movable into stopping engagement with and normally disengaged from said member, a power-shifting device arranged to be moved by coaction with said member when stopped, a pawl-releaser connected with said device and having a shoulder positioned to exert releasing pressure against said pawl on movement of said device, an 115 electric circuit, an electro-magnet controlled by said circuit and arranged to move said pawl to stopping position, and a circuit-closer for said circuit.

6. A stop mechanism comprising a member normally having continuous movement, 120 a stop member movable into engagement with and thereby stopping said member, a power-shifting device arranged to be moved by coaction with said member when stopped, 125 a stop-releaser, means causing said stop-releaser to push in releasing direction against said stop after institution of action of said power-shifting device, a normally-closed circuit-breaker and means whereby it is opened 130

4
after institution of action of said power-shifting device, an electric circuit including said circuit-breaker, an electro-magnet controlled by said circuit and arranged to move said stop member to stopping position, and a circuit-closer for said circuit.

7. A stop mechanism comprising a member normally having continuous movement, a pawl movable into stopping engagement with and normally disengaged from said member, a power-shifting device arranged to be moved by coaction with said member when stopped, a spring connected with said device and having a shoulder positioned to exert releasing pressure against said pawl on movement of said device, a normally-closed circuit-breaker arranged to be opened by movement of said device, an electric circuit including said circuit-breaker, an electro-magnet controlled by said circuit, and arranged to move said pawl to stopping position, and a circuit-closer for said circuit.

8. A stop mechanism comprising a member normally having continuous movement, a pawl movable into stopping engagement with and normally disengaged from said member, a power-shifting device arranged to be moved by coaction with said member when stopped, a pawl-releaser connected with said device and having a shoulder positioned to exert releasing pressure against said pawl on movement of said device, a normally-closed circuit-breaker arranged to be opened by movement of said device, an electric circuit including said circuit-breaker, an electro-magnet controlled by said circuit and arranged to move said pawl to stopping position, and a circuit-closer for said circuit. 25
